UNITED STATES PATENT OFFICE.

SAMUEL KAHN AND WILLIAM REIZENSTEIN, OF NEW YORK, N. Y.

DESIGN FOR A DOLL.

No. 38,809.

Specification for Design.

Patented Sept. 17, 1907.

Application filed August 19, 1907. Serial No. 389,303. Term of patent 8½ years.

To all whom it may concern:

Be it known that we, SAMUEL KAHN and WILLIAM REIZENSTEIN, citizens of the United States, and residents of the city of New York, borough of Manhattan, in the county and State of New York, have invented a new, original, and ornamental Design for a Doll, reference being had to the accompanying drawings, in which—

We claim:

The ornamental design for a doll as shown.
SAMUEL KAHN.
WILLIAM REIZENSTEIN.
